UNITED STATES PATENT OFFICE.

CHARLES N. GRAVES, OF SHREVEPORT, LOUISIANA, ASSIGNOR TO THE GRAVES TOOL CO., INC., OF SHREVEPORT, LOUISIANA, A CORPORATION OF LOUISIANA.

SPRING COMPRESSOR.

Application filed January 14, 1922. Serial No. 529,212.

To all whom it may concern:

Be it known that I, CHARLES N. GRAVES, a citizen of the United States, residing at Shreveport, in the parish of Caddo and 5 State of Louisiana, have invented new and useful Improvements in Spring Compressors, of which the following is a specification.

My present invention has reference to a 10 means for compressing the springs on the valve stems of automobiles to permit of the sustaining means for the springs and for freeing the valve from the stem to permit of the grinding of the valve or the removal 15 thereof from its seat.

The primary object of the invention is to produce a tool for this purpose which can readily be adjusted to act on different sized valves and springs and which will compress 20 the spring in an easy and expeditious manner without danger of breaking the stem.

A still further object is to produce a valve spring compressor by the use of which the spring can be compressed to any desired 25 predetermined degree.

A still further object is to produce a valve compressor in which the body portion thereof is in the nature of an angle frame that has its lower offset end provided with adjustable jaws whereby the same can straddle 30 valve stems of varying diameters to engage with the lower convolution of the spring thereon, while movable through the upper end of the frame is a plunger spring influenced 35 in an outward direction and having swiveled on its lower end a concaved head which is arranged over the valve, the said plunger being movable through a standard association with the frame, the said plunger 40 having its outer end bifurcated and provided with spaced openings through any one of which there is passed a pivot pin that also passes through any one of a plurality of staggered openings in the flat peripherally 45 round head of the operating handle, the periphery of the said head being in contact with a roller associated with the plunger, and a downward swinging of the handle will move the frame upwardly, causing the 50 jaws at the lower end of the frame to compress the spring to permit of the operator readily removing the means which secure the spring on the valve stem, and thus disassociate the spring and stem to permit of 55 the grinding or the removal of the valve.

The drawings illustrate a satisfactory embodiment of the improvement reduced to practice, and wherein:—

Figure 1 is a view illustrating the operation of the improvement. 60

Figure 2 is a greatly enlarged side elevation of the improvement.

Figure 3 is a sectional view on the line 3—3 of Figure 2.

Figure 4 is a sectional view on the line 65 4—4 of Figure 3.

Figure 5 is a sectional view on the line 5—5 of Figure 2.

Figure 6 is a sectional view on the line 70 6—6 of Figure 2.

Figure 7 is a sectional view on the line 75 7—7 of Figure 5.

My improvement is preferably constructed entirely of metal, and the body portion thereof is in the nature of an angle frame. 75 The lower end of the frame is flat and offset, and is likewise reduced to provide a jaw 1. From the jaw, the frame is continued at an upward and outward angle, as indicated by the numeral 2, the said angle portion, at a 80 suitable distance from the jaw being arranged at an inward angle parallel with the jaw. This last mentioned portion is indicated by the numeral 3 and is provided, adjacent its end, with an opening which is surrounded by an outstanding tubular standard 85

4. The bore of the standard and the opening through the portion 3 of the frame align, and the standard, from its outer end is centrally cut away or bifurcated in a line 90 parallel to the plane of the upper portion 3 of the frame. This bifurcation provides the upper end of the standard with spaced arms 5 respectively, and the said arms have a plurality of spaced aligning openings 95 6 therethrough.

Slidable in the standard and through the opening at the upper portion 3 of the frame there is a cross sectionally rounded plunger 7. The plunger has its end which extends through the opening in the upper portion 3 of the frame reduced and formed with a ball head 8 that is received in a spherical pocket 9 in a head member 10. The head has its upper portion formed with a neck 11 which is bent over the upper portion of the ball head 8, so that the head 10 is swiveled on the plunger. The head is round in cross section, and the lower or outer face thereof is concaved, as at 12. The upper end 110

of the plunger 7 is bifurcated in a line with the bifurcated portion of the standard, and between the arms 13 thus provided there is journaled a roller 14. Below the 5 roller there is passed through the plunger a pin 15 which is of a greater length than the thickness of the plunger, and surrounding the standard, contacting with the pin 15 and resting on the wall or shoulder 10 provided by the upper portion 3 of the frame at the juncture of the tubular standard 4 therewith there is a coiled spring 16. The spring thus influences the plunger in an upward or outward direction through the tubular standard. The head 10 of the plunger 15 is of a greater cross sectional diameter than that of the plunger, and consequently will be brought to contact with the under face of the upper portion 3 of the frame by the 20 influence of the spring and so limit the upward or outward movement of the plunger.

The operating handle for the device is indicated by the numeral 17, the same having one of its ends provided with a flat 25 peripherally rounded head 18, and this head is received in the bifurcated upper end of the tubular standard 4. The head 18 is provided with any desired number of staggered openings 19 therethrough, any one of 30 which designed to be brought to align with the registering openings 6 in the arms 5 of the standard, and through these aligning openings there is passed a removable pin 20. In this manner, it will be noted that 35 the head 18 may be adjusted with respect to the roller 14, and that the arrangement permits of a determined movement of the plunger against the pressure of its spring, on the operation of the handle 17 in a direction toward the frame. As a consequence, 40 the spring 21 on the stem 22 of a valve 23 in an engine head 24 may be compressed to a desired extent.

As previously stated, the jaw 1 is offset 45 with respect to the frame. The frame, inward of the jaw is formed with a longitudinal notch 25 on the side thereof opposite the jaw. From the outer side and adjacent the ends of the notch there are projected two pins 26 respectively, and between the pins there is a threaded opening. The shank or body portion 27 of a movable jaw 28 is provided with openings through which the pins 26 pass and with a central opening 50 that aligns with the referred to threaded opening in the notch portion of the frame. The outer face of the shank or body 27 is reamed in a line with the last mentioned opening to provide for the reception of the 55 head 29 of a screw 30, the said screw passing through the said opening and engaging the threads in the referred to opening in the frame. Surrounding the shank of the screw, and exerting a pressure between the wall of 60 the notch 25 and the inner wall of the shank 65

or body of the movable jaw 28 there is a spring 31. The head 29 of the screw is, of course, kerfed and by the employment of a suitable instrument, the screw can be turned, and in turning will adjust the movable jaw 70 with respect to the stationary jaw, with the result that varying sizes of valve stems may be received between the jaws. The pins 26 not only serve as guides for the movable jaw but also as bracing or reinforcing elements therefor when a spring is engaged 75 between the jaws.

It is believed that the foregoing description, when taken in connection with the drawings will fully set forth the construction, operation and advantages of the improvement to those skilled in the art to which such inventions relate without further detailed description, but it is thought necessary to add that I am not to be restricted to the precise structural features herein set forth but may, in the manufacture of my improvement resort to such changes and modifications as fall within the scope of what I claim.

It is to be noted that with the improvement, compressive force is obtained through the use of the eccentrically mounted head operating against the wheeled frame, which is in counter-distinction to ordinary valve lifters that employ the screw and lever principle, and also that after the compressing operation is completed, the device is self-locking, or in other words the eccentrically mounted pin is automatically held against movement when the plunger has been operated thereby, so that the employment of triggers, ratchets, pins, etc., is not required with the device.

Having described the invention, I claim:—

1. An angle frame having its lower end offset to provide a jaw, a second jaw opposite the first mentioned jaw, guide means for the last mentioned jaw, means for adjusting the last mentioned jaw with respect to the first mentioned jaw, a hollow standard on the upper portion of the frame in a line with the jaw, a plunger movable in the standard and through the upper portion of the frame, a swiveled head on the lower end of the plunger below the frame, a roller journaled in the upper end of the plunger, spring means between the frame and plunger influencing the latter outward through the standard, and swingable means 110 adjustably associated with the standard for contacting the roller to move the plunger in an opposite direction.

2. An angle frame, jaws one adjustable with respect to the other on the lower end 125 of the frame, a tubular standard having an outer bifurcated and apertured portion on the upper end of the frame in a line with the jaws, a cross sectionally rounded plunger movable in the standard and 130

through the frame, a head swiveled on the lower end of the plunger and having its outer face concaved; a pin passing through the plunger and through the bifurcated portion of the standard, a spring surrounding the standard and exerting a pressure between the pin and frame, a roller journaled in the upper end of the plunger, an operating handle having a flat peripherally

rounded head received in the bifurcated portion of the standard, said head having staggered openings therethrough, one of which designed to be brought to align with certain of the apertures in the standard, and a pin passing through these aligning apertures, as and for the purpose set forth.

In testimony whereof I affix my signature.

CHARLES N. GRAVES.
